(57) **CLAIM**

The ornamental design for a display screen or portion thereof with graphical user interface, as shown and described.

DESCRIPTION

FIG. 1 is a front view of the display screen or portion thereof with graphical user interface according to a first embodiment of our claimed design; and,

FIG. 2 is a front view of the display screen or portion thereof with graphical user interface according to a second embodiment of our claimed design.

The outermost dot-dashed broken lines show the display screen and form no part of the claimed design. The interior dot-dashed broken lines show a boundary and form no part of the claimed design. The grayscale area between the outermost and interior dot-dashed broken lines forms no part of the claimed design. The dash-dot broken lines show part of the graphical user interface that forms no part of the claimed design.
